Primary Examiner — Paula Allen Greene

(74) Attorney, Agent, or Firm — Banner & Witcoff, Ltd.

(57) **CLAIM**

The ornamental design for a headset, as shown and described.

DESCRIPTION

FIG. 1 is a front perspective view of a headset showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is an additional front perspective view of the design showing one earcup in isolation for clarity purposes; and, FIG. 9 is an additional right side view thereof.

The broken lines depicting the remainder of the headset in FIGS. 1-9 show features that form no part of the claimed design.
